(57) **CLAIM**

The ornamental design for a tent pole ground anchor and support device, as shown and described.

DESCRIPTION

FIG. 1 is a perspective view of a first embodiment of a tent pole ground anchor and support device embodying my new design;

FIG. 2 is a top plan view of the first embodiment;

FIG. 3 is a side elevational view of the first embodiment;

FIG. 4 is a side elevational view opposite that shown in FIG. 3;

FIG. 5 is an end elevational view of the first embodiment;

FIG. 6 is an end elevational view opposite that shown in FIG. 5;

FIG. 7 is a bottom plan view of the first embodiment;

FIG. 8 is a perspective view of a second embodiment of a tent pole ground anchor and support device embodying my new design;

FIG. 9 is a top plan view of the second embodiment;

FIG. 10 is a side elevational view of the second embodiment;

FIG. 11 is a side elevational view opposite that shown in FIG. 10;

FIG. 12 is an end elevational view of the second embodiment;

FIG. 13 is an end elevational view opposite that shown in FIG. 12; and,

FIG. 14 is a bottom plan view of the second embodiment.
